MOTOR VEHICLE

Eugene R. Fox, Minneapolis, Minn., assignor to Cat-A-Gator Corporation, Hopkins, Minn., a corporation of Minnesota

Filed Dec. 2, 1965, Ser. No. 25

Term of patent 14 years

(Cl. D14—3)

FIG. 1

FIG. 2

FIG. 3

FIG. 4

FIG. 5

FIG. 6

FIG. 1 is a view in perspective of a motor vehicle seen from the front and one side, showing my new design;

FIG. 2 is a view in perspective of the vehicle of FIG. 1, as seen from the rear and opposite side;

FIG. 3 is a view in top plan;

FIG. 4 is a view in side elevation;

FIG. 5 is a view in front elevation; and

FIG. 6 is a view in rear elevation, some parts being broken away.

I claim:

The ornamental design for a motor vehicle, as shown.
